UNITED STATES PATENT OFFICE.

ROBERT W. WIEDERWAX, OF ATLANTIC CITY, NEW JERSEY, ASSIGNOR OF ONE-HALF
TO CARLTON GEIST, OF ATLANTIC CITY, NEW JERSEY.

FLUID-FUEL FURNACE FOR HEATING CASTINGS.

1,234,240.

Specification of Letters Patent. Patented July 24, 1917.

Application filed February 13, 1917. Serial No. 148,815.

To all whom it may concern:

Be it known that I, ROBERT W. WIEDERWAX, a citizen of the United States, residing at Atlantic City, in the county of Atlantic 5 and State of New Jersey, have invented certain new and useful Improvements in Fluid-Fuel Furnaces for Heating Castings, of which the following is a specification.

My invention relates to a fluid fuel operated furnace for properly heating castings, particularly hollow castings, such as the cylinders of an engine, etc., preparatory to or in connection with welding, for preventing cracking or distorting of the casting, due to such heating or cooling after 15 heating.

As far as I am aware, at the present time, the heating of castings or the like, preparatory to or in connection with their welding, 20 is accomplished by means of charcoal or a charcoal operated furnace. I am aware that attempts have heretofore been made to provide heating machines of this character, employing gas or oil as fuel, but such machines have not proven wholly satisfactory.

In the heating of castings, particularly hollow castings, prior to or in connection with welding, it is necessary to evenly or uniformly heat all portions of the casting, 30 thus preventing cracking or distortion thereof. When heating automobile cylinders, should the same become distorted or warped due to uneven heating of portions thereof, it is necessary to re bore the cylinder.

As far as I am aware, at the present time, the only successful means for properly heating castings is by the employment of charcoal or a charcoal operated furnace, which 35 is disadvantageous inasmuch as the process is slow and expensive.

An important object of the invention is to provide a furnace of the above mentioned character, by the employment of which all portions of the casting may be evenly heated 40 and cooled, effectively preventing cracking or warping.

Other objects and advantages of the invention will be apparent during the course of the following description.

50 In the accompanying drawings forming a part of this specification and in which like numerals are employed to designate like parts throughout the same,

Figure 1 is a side elevation of apparatus 55 embodying my invention,

Fig. 2 is a plan view of the same,

Fig. 3 is a longitudinal sectional view taken on line 3—3 of Fig. 2,

Fig. 4 is a transverse sectional view taken on line 4—4 of Fig. 1, 60

Fig. 5 is a side elevation of a car or carriage, included in the apparatus,

Fig. 6 is a perspective view of the brake bar or rod, and,

Fig. 7 is a similar view of a heat absorbing member. 65

In the drawings, wherein for the purpose of illustration is shown a preferred embodiment of my invention, the numeral 10 designates the body portion or shell of the 70 furnace, which is preferably formed of sheet metal, while the same may be made of any other suitable material. The upper portion of the shell 10 forms a heating chamber 11 open at its top and which is 75 preferably lined with a refractory material, such as fire tile or brick 12, as shown. Arranged beneath the heating chamber 11 is a dump box or chamber 13, one side of which has an opening which is normally closed by 80 a preferably vertically swinging door 14, which may be retained closed by any suitable means.

As more clearly shown in Figs. 2 and 3, the numeral 15 designates removable horizontal grate bars, arranged between the heating chamber 11 in the dump box 13. The forward end of these grate bars are detachably supported by means of sockets 16 or the like, rigidly secured to the end wall 90 17 of the box 13, while their opposite ends are arranged upon the top of the end wall 18 of the box, the corresponding end of the heating chamber 11 being open, as shown.

Extending longitudinally through the 95 shell 10 in proximity to the bars 15 are horizontal track rails 19, which are supported by the end wall 18 and have their forward ends projecting into sockets 20, fixed to the end wall 17. It is obvious that these track 100 rails can be removed if desired. The track rails 19 extend rearwardly beyond the furnace for any suitable distance and are supported by any suitable means (not shown).

Adapted to travel upon the track rails 19 105 is a car or carriage 21, having flanged wheels 22 to engage with the rails.

As above stated, the rear end of the heating chamber 11 above and adjacent the end wall 18 is open, and this open end may be 110 closed by a vertically sliding door 23, operating in vertical guides 24. The side walls

of the heating chamber 11, adjacent the rear ends thereof, and at the tops are connected by a transverse bar 25, preferably arranged exteriorly of the sliding door 23. The door 23 has connection with a flexible element, such as a cable 26, passed about the grooved pulleys 27 and having connection with a counter-weight 28. The door 23, is preferably equipped with a handle 29 for raising and lowering it, and this door also has an opening 30 for receiving a long casting or member to be heated. The opening 30 may be covered by a movable plate 30'. The forward end wall 31 of the heating chamber 11 is provided with an opening 32 normally covered by a movable plate 32', in registration with the opening 30, when the door 23 is in the lowermost position.

The side walls 11' of the heating chamber 20 11 are provided with openings 33, receiving gas burner tips 34, connected with pipes 35. The upper and lower sets of gas burner tips 34 extend inwardly for a substantial distance beyond the intermediate burner tips.

25 The function of having these tips 34 of different lengths, as stated, is to provide means whereby the free ends of the same will be arranged at approximately equal distances from the center of the casting 42, thereby 30 evenly distributing the heat to the casting. These pipes 35 are connected with horizontal pipes 36, through the medium of valves 37 and associated elements. The pipes 36 are connected with a common gas feed pipe 38, having a cut off valve 39 connected therewith. Connected with one pipe 36 is a pilot light burner 40, projecting into the chamber 11 and having a valve 41 connected therein.

40 In the operation of the apparatus, the casting to be heated, in the present illustration, the cylinder 42 of an engine, is placed upon the car 21, and the car is pushed into the heating chamber 11. The grate bars 15 are then arranged in place and the door 23 45 is moved to the lower or closed position. The space between the casting 42 and the walls of the heating chamber 11 is filled with heat absorbing and radiating elements 43, which may be formed of fire clay and 50 silica, such elements being of suitable size, as shown. This having been done, the pilot light 40 being lighted, upon turning on the gas to the burner tips 34 by opening valves 37, these burner tips will be lighted and the flame and products of combustion discharged into the heating chamber 11, in the presence of the heat absorbing elements 43. These heat absorbing elements take up the heat and 55 transmit the same to the casting 42, so that all portions of the casting are evenly heated.

60 At the end of the heating period, the rods 15 are first removed, and the elements 43 drop into the box 13, and may be removed

by swinging the door 14 open. The door 23 is now elevated and the carriage 23 moved 65 out of the heating chamber 11. The heated casting is now moved to the welding machine and the same is welded.

After this treatment, it is necessary that the casting be cooled gradually so that all 70 portions thereof remain at substantially the same temperature and for this purpose, burner tips 34 being first extinguished, the casting is reintroduced into the heating chamber 11. The heated elements 43 are 75 again piled in the heating chamber 11 about the casting and gradually give up or radiate their heat, thus causing the casting to cool gradually and evenly.

It is to be understood that the form of my 80 invention herewith shown and described is to be taken as a preferred example of the same, and that various changes in the shape, size, and arrangement of parts may be resorted to without departing from the spirit 85 of the invention or the scope of the subjoined claims.

Having thus described my invention, I claim:

1. In apparatus of the character described, 90 a heating shell having its side walls provided with sets of openings, burner tips extending into the heating shell through the openings, the upper and lower tips extending inwardly for a substantially greater distance than the intermediate tips, and means to supply fluid fuel to the tips.

2. In apparatus of the character described, an upstanding shell having its top open and provided with an upper heating chamber in 100 free communication with the opening in the top and a lower dump chamber having an opening for the withdrawal of material therefrom, a removable grate arranged approximately horizontally between the heating chamber and the dump chamber, a track extending into the shell and having an approximately horizontal portion arranged adjacent the removable grate, a carriage to travel upon the track and adapted to be 110 passed into the upstanding shell through one open end thereof and receive and support the casting or the like to be heated, a movable door for closing the open end of the upstanding shell, heat absorbing and radiating elements disposed within the shell and supported by the removable grate, and means arranged within the upstanding shell 115 to heat the elements.

120 In testimony whereof I affix my signature in presence of two witnesses.

ROBERT W. WIEDERWAX.
